UNITED STATES PATENT OFFICE

THOMAS M. WOOD, OF BOSTON, MASSACHUSETTS, ASSIGNOR TO CONDIT ELECTRICAL MANUFACTURING CORPORATION, OF SOUTH BOSTON, MASSACHUSETTS, A CORPORATION OF MASSACHUSETTS

AUXILIARY SWITCH

Application filed March 4, 1926. Serial No. 92,371.

This invention relates to circuit-interrupters of the truck type and to auxiliary switches especially adapted for use in connection with such interrupters, although not necessarily limited to such use.

A truck-type circuit interrupter is usually electrically-operated and so carries closing and opening coils, as well as various circuit-controllers arranged to change the conditions of various circuits when the interrupter opens and closes. The interrupter is adapted to be rolled into a cell and automatically to establish connection with the circuit it is adapted to control and to break such connection when being withdrawn from the cell. Auxiliary switches are also provided, the movable components of which are carried by the interrupter, and these switches are adapted automatically to connect and disconnect the opening and closing coils, and other accessory devices, with and from their various control circuits at the insertion or removal of the interrupter. A single interrupter may have a large number of auxiliary switches associated with it.

Considerable difficulty has been experienced in maintaining good alignment between the separable contact members of the auxiliary switches, and in maintaining good and reliable contact between the contact members thereof, due to variations from specified dimensions in assembly, wear and the like and especially due to the impracticability of working to accurate dimensions in pouring the cement of the cell construction.

An object of this invention is the provision of an auxiliary switch having a yieldingly supported movable contact member so constructed and arranged that it has a wide range of yielding movement, thereby to establish good electrical contact with its cooperating fixed member regardless of relatively great departures from their relative designed positions.

A further object is the provision of a truck type switch provided with an auxiliary switch having a movable contact member which is self-seating on its cooperating movable contact member, whereby to have a bear-

ing thereon over practically its entire contact-area regardless of a considerable departure from the intended settings of the contact members.

A further object is generally to improve the construction and operation of electric switches.

Fig. 1 is a side elevation of a truck-type circuit interrupter with an auxiliary switch embodying this invention associated with it.

Fig. 2 is a detailed side elevation illustrating a gang of auxiliary switches embodying the invention.

Fig. 3 is a sectional view taken along line 3-3 of Fig. 2.

Fig. 4 is a side elevation of the movable components of the auxiliary switch.

Fig. 5 is a view similar to Fig. 4 but illustrating how the contact members preserve full contact when their supporting structures are out of line.

The circuit interrupter with which the auxiliary switch embodying this invention is adapted especially to be associated includes the enclosing casing 10 which is mounted on wheels 12 and is adapted to roll on a track 14 into and out of an enclosing cell 16. The terminals 18 and 20 of the interrupter are provided with disconnecting contact members 22 and 24 which are adapted detachably to engage the stationary disconnecting contact terminals 26 and 28 of a power circuit. The arrangement is such that when the interrupter is moved into the cell, the said contact members are caused to inter-engage and thereby to connect the interrupter automatically with the power circuit, and when the interrupter is moved outwardly, its connection with the power circuit is interrupted.

The interrupter here shown is electrically operated and has a closing magnet 30 and an opening magnet 32. A circuit-controller 34 is or may be provided, also, for giving remote indications of the conditions of the interrupter and for otherwise altering the condition of suitable circuits.

Auxiliary switches embodying the present invention are provided for automatically making and disconnecting the various circuits associated with the interrupter, as the

circuits for the opening and closing coils and for the circuit controller, when the circuit interrupter is moved into and is withdrawn from operative position within its enclosing cell. The movable components of the auxiliary switches are mounted, in spaced parallel relation with each other, on an insulating bar 36, which bar is disposed horizontally above the interrupter in the upper front portion of the cell, when the interrupter is therein, and is supported rigidly in position by means including a frame 38 carried by the interrupter. The stationary components of the auxiliary switches are carried by a similar bar 40, which bar is attached rigidly to the cell structure in such position that it is vertically spaced above the bar 36, when the interrupter is in operative position within the cell.

The auxiliary switches are identical in construction and the construction of but one need be described. The stationary contact member comprises mainly a flat plate 42 which is attached to the lower face of said upper insulating bar 40 by any suitable means as the screws 44. Said plate has a flat horizontal lower surface which is adapted to be engaged by the movable contact member. The front end of said plate is provided with an up-turned lip 46 which serves to guide the movable contact member onto the lower contact face of the plate. The rear end of said plate is provided with a similar lip 48 which is provided with attaching means 50 for a circuit lead 52. The plate preferably is symmetrically formed so that either lip may be placed in front.

The movable switch member includes two brackets 54 and 56. Each bracket comprises the spaced and parallel side walls 58 which are outwardly extended from a connecting wall 60 which is integral with said side walls. Attaching bolts 62 may pass through said walls 60 of both brackets and through the insulating supporting bar 36, whereby to secure all together. Said walls 58 are extended upwardly and outwardly to a point above the top of said bar 36 and pivot pins 64 pass through said walls. Link-members 66 and 68 are supported on said pins. Said link-members are identical. Each comprises a channel-member having the spaced and parallel side-arms 70 and the integrally-connected wall 72. Said side-arms 70 are formed with slots 74 therein which lie along the length of said arms, at the outer ends thereof, and in which slots said pivot pins 64 are loosely received. The movable contact member is adapted to be carried by the proximate ends of said link-members.

Said movable contact member comprises a channel member 76 which has the flat upper wall 78 and the depending and integrally-connected side walls 80. The proximate ends 82 of said link-members are disposed between

said side-walls and are pivotally connected loosely to the opposite ends of said walls by pivot pins 82. Coiled springs 84 encircle said pins 82 and the ends of said springs bear upon the walls 72 of the link-members and also upon a pin 86 which is carried by said walls 80 and disposed between the proximate ends of said link-members. The arrangement of said springs is such as to maintain the movable contact member yieldingly in its most elevated position, as shown in Fig. 4, in which position the bottoms of the slots 74 in the link-members are brought up against the pins 64, which restricts the structure from further movement under the action of said springs.

The movable contact member is provided with a flat upper face which is adapted to seat upon the flat lower face of the fixed contact member, when the two are in proper engagement. The movable contact member is also provided with depending end-lips 88 which cooperate with the lips 46 and 48 of the fixed contact member in guiding the movable contact member to position against the fixed contact member.

A flexible conductor 90 is secured to the movable contact member, by solder or otherwise, and also is connected to one of said bolts 62, as the lower bolt, which bolt thereby provides a terminal connection for the movable switch member.

Due to the support provided for the movable contact member, it can pivot about each link-member, or can be inclined in both directions about a horizontal axis, as well as move downwardly in parallel lines while maintaining its contact face horizontal. By providing a loose connection between the link-members and the pivot-pins 64, the movable contact member may have, also, a suitable amount of side-wise movement in both directions. It has, therefore, a universal support, and so can align itself with the fixed contact member, under all usual conditions encountered in practice.

The movable components of the auxiliary switch above set forth are adapted to be moved in a horizontal line into and out of engagement with the stationary contact member, as the circuit interrupter is moved into and out of its enclosing cell. The movable contact member, when withdrawn from contact engaging position, normally is supported in a position which is higher than its contact-engaging position. As the interrupter is moved into the cell, the rear lip 88 engages with the forward lip 46 of the fixed contact member and so inclines the movable contact member downwardly. Further movement in the same direction serves to straighten the link-members and to bring the movable contact member under the flat face of the fixed contact member, upon which the movable contact member will seat and bear over prac-

tically its entire extent, adjusting itself on said link-members to this end.

The supporting means for the movable contact member provides a relatively great range 5 of vertical positions which the contact member may occupy while maintaining good electrical contact with the fixed contact member.

This construction may be otherwise modified without departing from the spirit of the 10 invention.

I claim:

1. In an electric circuit controller, the combination of an upper stationary contact member having a horizontal flat intermediate portion and upwardly inclined end portions, an insulating support for said member, a lower and cooperating contact member which is horizontally movable into and out of engagement with said fixed contact member having a horizontal flat intermediate portion cooperating with the flat intermediate portion of said fixed contact member and downwardly-inclined portions located at the opposite ends of said intermediate portion, a horizontally 20 movable insulating bar disposed beneath said movable contact member comprising a movable support therefor, brackets located separately on opposite sides of said bar, links having pivotal connections with said movable 25 contact member and having pin and slot connections with said brackets, and resilient means separately engaging said movable contact member and said links arranged to urge them in opposite directions and thereby urge 30 said movable contact member for movement upwardly above said insulating bar.

2. In an electric switch, upper and lower insulating supports, a stationary contact member attached to and transversely of the lower face of said upper support, a cooperating movable contact member disposed transversely above said lower support having depending spaced side walls, a pair of arms disposed beneath and extended in opposite 5 directions beyond said contact member, said arms comprising channel-members having integral upstanding spaced side walls received between the side walls of said contact member, pivot pins carried by the walls of said 10 contact member, at opposite ends thereof, and passed loosely through the walls of said arms, at the upper ends thereof, springs encircling said pivot pins and having separate bearings on said arms and also on said contact member, 15 separate opposed brackets carried by said lower support on opposite sides thereof and having integral upstanding spaced side walls, between which the free lower ends of said arms are received, said arms having longitudinally-directed opposed slots in the lower 20 ends of the walls thereof, and pivot-pins carried by the walls of said brackets passed freely through said slots.

3. In an electric circuit controller, the combination of a pair of upper and lower insulat-

ing bars, one of which is horizontally movable beneath the other into and out of a circuit controlling position, a stationary contact member carried by said upper bar transversely across the bottom face thereof having a flat intermediate section and outwardly and upwardly inclined end sections which guide a cooperating movable contact member onto said flat intermediate section, a cooperating movable contact member carried by and transversely of said lower bar and disposed for movement horizontally into and out of engagement with said stationary contact member comprising a channel-shaped member having a flat intermediate section engageable with the flat intermediate section of said stationary contact member and downwardly inclined end sections located at the ends of said flat intermediate section cooperating with the upwardly inclined end section of said stationary contact member and vertically depending and spaced side walls, and supporting mechanism for said movable contact member which permits it to yield in a vertical direction including a pair of separate brackets disposed beneath said contact member on opposite sides of and carried by said lower insulating bar, links having pin and slot connections with the upper ends of said brackets and having their proximate ends located between said depending side walls of said movable contact member, means separately pivotally connecting said ends with said movable contact member, and means supporting said movable contact member yielding in elevated position above said lower insulating bar including spring means bearing on said movable contact member and separately on each of said links in a direction to urge them in opposite directions and thereby to urge said movable contact member upwardly.

4. In an electric circuit controller, upper and lower insulating bars, the lower bar being movable horizontally into and out of circuit controlling position with respect to said upper bar, a contact member carried by and secured to and transversely of the lower face of said upper insulating bar having a flat horizontal intermediate section and upwardly inclined end sections, one of said inclined end sections constituting a terminal of the circuit controller and having attaching means for a circuit conductor, a cooperating movable contact member carried by said lower insulating bar and transversely above the upper face thereof comprising a channel member having a flat intermediate section engageable with the flat section of said stationary contact member and downturned walls at the sides of said intermediate section and downwardly inclined sections extended from the ends of said intermediate section and cooperating with the upturned end sections of said stationary contact member, and

means to support said movable contact member in elevated position above said lower insulating bar including a pair of independent brackets located on opposite sides of and carried by said lower insulating bar, attaching means passed through the both of said brackets and said insulating bar and connecting said brackets and bar rigidly, a flexible lead secured to said movable contact member and to said attaching means, said attaching means thereby constituting a second terminal of said circuit controller and having attaching means for a circuit conductor, links having pin and slot connections with said brackets having their confronting ends located between the downwardly extended side walls of said movable contact member, means separately pivotally connecting said ends with said contact member, and means supporting said movable contact member yielding in elevated position above said lower insulating bar including springs bearing on said movable contact member and separately on said links in a direction to move said movable contact member upwardly.

5. In an electric circuit controller, the combination of upper and lower insulating bars, said lower bar being movable horizontally into and out of circuit controlling position with respect to said upper bar, a stationary contact member carried by and secured to the lower face of said upper bar, a movable contact member carried by and located transversely above said lower bar, said movable contact member comprising a channel-shaped member having a flat intermediate contact section and downwardly inclined sections located at the opposite ends of said contact section and having downwardly directed opposed side walls, supporting means for said movable contact member including independent brackets having flat intermediate sections and integral parallel spaced walls which upstand above said intermediate sections, and also above said bars, means passed through said intermediate sections and said lower insulating bar securing said brackets on opposite sides of said lower bar, links connecting said brackets and said movable contact member having intermediate sections and upturned integral side walls, the ends of which are located between the upstanding side walls of said brackets and the downwardly extended side walls of said movable contact member, said links having pin and slot connections with the side walls of said brackets, pivot pins passed separately through the ends of said links and the side walls of said movable contact member, an abutment pin located between said pivot pins and carried by the side walls of said movable contact member, and means supporting said movable contact member yielding in elevated position above said lower insulated bar including springs separately

encircling said pivot pins and having bearings on said abutment pin and separately on said links.

In testimony whereof, I have signed my name to this specification.

THOMAS M. WOOD.
